UNITED STATES PATENT OFFICE.

HOMER H. INGERSOLL AND CLARENCE B. INGERSOLL, OF CHICAGO, ILLINOIS,
ASSIGNORS, BY DIRECT AND MESNE ASSIGNMENTS, TO INGERSOLL ELECTRIC VAPORIZER CO., A CORPORATION OF ILLINOIS.

FUEL-VAPORIZER FOR EXPLOSION-ENGINES.

1,106,386.

Specification of Letters Patent. Patented Aug. 11, 1914.

Application filed November 3, 1913. Serial No. 798,904.

To all whom it may concern:

Be it known that we, HOMER H. INGERSOLL and CLARENCE B. INGERSOLL, citizens of the United States, and residents of the city 5 of Chicago, county of Cook, and State of Illinois, have invented certain new and useful Improvements in Fuel-Vaporizers for Explosion-Engines, of which the following is a specification.

10 Our invention relates to a fuel vaporizer for explosion engines.

At the present time considerable difficulty is not infrequently experienced by automobile drivers in endeavoring to start the engine in cold weather. This of course is caused by the cool condition of the engine and the fuel passages leading thereto which results in the inability to vaporize or gasify the liquid fuel.

20 It is the object of this invention to provide means for heating and hence vaporizing liquid fuel in its passage to the engine cylinder which will be as effective in cold weather as in warm and hence whereby the 25 engine may be readily started irrespective of the outside temperature.

A further object is the production of a device as mentioned which will be of simple and economical construction and efficient in 30 use.

Other objects will appear hereinafter.

The invention consists in the combinations and arrangements of parts hereinafter described and claimed.

35 The invention will be best understood by reference to the accompanying drawing forming a part of this specification, and in which—

Figure 1 is a front elevation of a conventional intake pipe of an explosion engine equipped with a vaporizing device embodying our invention, Fig. 2 is an enlarged section taken on substantially line $x-x$ of Fig. 1, and Fig. 3 is a section taken on substantially line $y-y$ of Fig. 2.

The preferred form of construction as illustrated in the drawing comprises a holder or body 1 preferably of the form and proportions shown. Arranged centrally in 50 the member 1 is a ring 2 of noncombustible material, metal being preferably used which is removably secured in position in the member 1 by means of insulating material 3. One side of the member 1 is recessed, as

clearly shown in Fig. 3, to accommodate the 55 ring 2, the insulating material 3 serving to effectually insulate said ring of said holder. In the event of the holder being itself formed of insulating material it will of course be unnecessary to insulate the ring 2 60 therefrom, the insulation of said ring from said holder being resorted to only when the latter is formed of a conducting material.

Arranged in the ring 2 is a heating element 4 formed of a band or strip of material of high electrical resistance. The member 4 is bent upon itself in a tortuous manner as shown so as to form a plurality of parallel spaced blades which traverse the passage or opening through the member 2. 70 Said blades are preferably inclined, as clearly shown in Figs. 2 and 3, so as to increase the traversing effect thereof in the passage or opening in the member 2 while, at the same time, passage of fluid through 75 said member will be unimpeded and unobstructed. Said element 4 is insulated from ring 2 as illustrated, this insulation being however unnecessary if said member 2 is itself formed of insulating material. 80

The respective extremities of the element 4 are connected with binding posts or electrodes 5 which are mounted in the member 1 and which project exteriorly therefrom for connection with circuit wires of a source of 85 electrical energy 6.

In the employment of the device in connection with the fuel intake pipe of an explosion engine the same is interposed in said pipe, indicated at 7, in Fig. 1, being 90 rigidly secured between two flanges formed in said pipe by bolts or other suitable fastening devices 8. The arrangement is such that the opening through the member 2 will coincide with the passage through said intake pipe and so that element 4 will be interposed in said passage. This being so upon the passage of current from the source of electrical energy 6 through said element 4 which, because of the high electrical 100 resisting character of the latter causes heating thereof, the liquid fuel passing through said intake pipe will contact with or impinge upon said element and thereby become heated and hence vaporized or conditioned 105 for ignition. Through the inclination of the traversing fluid portions of the heating element 4, the contact of all particles of the

liquid fuel passing through the pipe 7 with said element is insured thereby resulting in the thorough heating of the fuel with the corresponding advantageous result in the ignition of the mixture as will be appreciated by those skilled in the art.

12 The device is of extremely simple construction and hence may be manufactured at a low cost. The component parts of the device are so connected that, in the event of one or more of said parts becoming disabled or worn out the same may be removed and replaced without destroying the remaining parts thereof.

15 While we have illustrated and described the preferred form of construction for carrying our invention into effect, this is capable of variation and modification without departing from the spirit of the invention.

20 We, therefore, do not wish to be limited to the precise details of construction set forth, but desire to avail ourselves of such variations and modifications as come within the scope of the appended claims.

25 Having described our invention what we claim as new and desire to secure by Letters Patent is:

1. The combination with a fluid passage, of means for heating the fluid passing through said passage, said means comprising an element of high electrical resistance con-

sisting of a plurality of substantially parallel spaced blades obliquely disposed in transverse arrangement interposed in and traversing said passage, said blades being 35 connected together to form a continuous electrical conductor; and a source of electrical energy connected with said element for passing an electrical current therethrough, substantially as described.

40 2. The combination with a fluid passage, of means for heating the fluid passing through said passage, said means comprising an elongated flat continuous integral element of high electrical resistance arranged in tortuous formation to constitute substantially parallel spaced blades obliquely disposed in transverse arrangement interposed in and traversing said passage; and a source of electrical energy connected 45 with said element for passing an electrical current therethrough, substantially as described.

50 In testimony whereof we have signed our names to this specification in the presence of two subscribing witnesses.

HOMER H. INGERSOLL.
CLARENCE B. INGERSOLL.
